UNITED STATES PATENT OFFICE.

JOHN D. BOWMAN, OF SEBRING, OHIO, AND THEODOR J. ROTH, OF MOUNT CLEMENS, MICHIGAN.

GLAZING MACHINE.

Application filed May 28, 1924. Serial No. 716,461.

To all whom it may concern:

Be it known that we, JOHN D. BOWMAN and THEODOR J. ROTH, both citizens of the United States, residing, respectively, at 5 Sebring, in the county of Summit and State of Ohio, and Mount Clemens, in the county of Macomb and State of Michigan, have invented new and useful Improvements in Glazing Machines, of which the following is 10 a specification.

This invention relates to machinery used in making pottery, tiles, and the like and has for its object the provision of a novel device for supporting, carrying and conveying 15 earthenware or pottery vessels, utensils or other articles in a continuous and automatic manner between spray nozzles or in the path of a spray or jet which applies to the articles the proper liquid which forms 20 the requisite glaze.

An important object is the provision of a machine of this character which is provided with means for effecting drying of the pottery subsequent to the application of the 25 glazing liquid thereto, so that by the time the articles leave the machine they will be in dry condition ready for any subsequent treatment which may be necessary.

Yet another object is the provision of a 30 device of this character which is provided with automatically acting drain means for collecting the surplus glazing material and returning the same to the storage tank or container holding the liquid, the advantage 35 being that there will be no waste of the solution or liquid.

Another object is the provision of a device of this character which includes peculiar means for holding the earthenware articles such means being replaceable by other 40 means for holding tiles or other flat articles which do not require glazing on one side.

An additional object is the provision of a machine of this character which is simple 45 and inexpensive in manufacture, highly efficient in use, durable in service and a general improvement in the art.

With the above and other objects and advantages in view the invention consists in 50 the details of construction to be hereinafter more fully described and claimed and illustrated in the accompanying drawings, in which:

Figure 1 is a side elevation of the device, 55 Figure 2 is a top plan view thereof,

Figure 3 is an end elevation,
Figure 4 is a central cross section,
Figure 5 is an enlarged horizontal section showing the rack and heating coil,

Figure 6 is a detail view showing the construction and mounting of one of the article carrying spindles,

Figure 7 is a detail perspective view of a support for holding a tile.

Referring more particularly to the drawings we have shown the machine as comprising a suitable supporting frame designated broadly by the numeral 10 and consisting of a pair of elongated longitudinal bars 11 carried at the upper ends of legs 12 which are 60 connected at each side of the machine by diagonal brace bars 13 arranged and secured in crossed relation as shown. The upper and lower ends of the legs are connected by cross bars 14. This frame might be constructed of 70 wooden bars or of angle or channel iron the latter being probably preferable though it should be understood that the material and the dimensions constitute mere details which 75 do not affect the principle of the invention.

Secured upon the end portions of the longitudinal bars 11 are bearings 15 within which are journaled shafts 16 and 17 upon which are secured pairs of sprockets 18 about which are trained endless chains 19 80 which are in turn trained about sprockets 20 on a shaft 21 journally supported from the braces 13. The sprockets 20 are idle and are solely for the purpose of tightening the chains, and the sprockets 18 are also idle. 85 The shaft 17 carries a pulley 22 driven by a belt 23 trained thereabout and engaged about a pulley 24 on the shaft of a suitable motor 25. This belt and pulley arrangement 90 might of course be replaced by a sprocket and chain arrangement or by a system of gearing as such mechanical elements are 95 equivalent and capable of interchangeable use.

The chains 19 are connected at regularly 100 spaced intervals by cross bars 26, each of which is formed with a bearing 27 through which is rotatable a spindle 28 carrying a gear 29 at its end below or inwardly of the bearing. The other ends of the spindles 105 carry preferably resilient divergent arms 30 adapted to support articles 31 to be glazed. In the present instance we have shown the articles as being rather shallow earthenware dishes though it should be understood that 110

any ordinary articles may be treated in this machine.

In conjunction with this carrier device use is made of one or two spray pipes or nozzles 32 as indicated and which lead from any suitable tank or the like containing the glazing liquid. The nozzles are shown as discharging downwardly, but if preferred others may be provided extending upwardly so 10 that the liquid sprayed out will coat the top and bottom sides of the articles. The present invention does not contemplate any specific spraying device as it is readily conceivable that different types might be used 15 depending upon the notion of the individual user or the maker of the complete machine.

In order to insure a uniform application of the liquid, we provide a rack 33 which is suitably mounted upon the frame of the machine at the intermediate portion of the space between the side bars 11 and located at such a position as to be engaged by the gears 29 as the carriers are moved along the machine. The moment a gear engages or 20 meshes with this rack it is apparent that the spindle carried thereby will be rotated, carrying with it the article to be coated so that when the article passes beneath the jets all 25 portions of its surface will be treated.

30 In case it is desired to coat tiles and the like instead of articles like dishes, the spindle sections which carry the arms 30 are replaced by flat, preferably flanged, plates 34 on which the tiles are laid.

35 An important feature is the provision of a drain pan 35 which is suitably mounted on the frame below the jet pipes and which is provided for the purpose of catching the surplus glazing material after it passes from the pottery or other ware being treated. This drain pan is provided with a pipe 36 for conducting the surplus material back to the storage tank or container not shown.

40 Located above and extending along the intermediate portion of the frame is a hood 37 which is of inverted U-shape. Within the entrance end of this hood are shields 38 suitably supported in spaced relation and having upwardly inclined top portions 39 and downwardly inclined intermediate portions 40 spaced apart as shown at 41 for the passage of the spindles carrying the ware. These shields prevent splashing and loss of the glazing liquid in an obvious manner. 45 The inclination of the lower shield members or portions operates to conduct the surplus liquid to the drain pan 35.

40 The remaining or rear end portion of the hood constitutes a dryer and heating is effected by means of a steam coil 42 which is

located and suitably mounted within the frame at this rear portion of the hood.

In the operation it will be seen that the articles to be glazed are placed upon the supporting spindles as they come up at the forward end of the machine. As the mechanism is operated, the endless chains will move from left to right of Figure 1 and will carry the articles into and through the shields and hood, the articles being rotated 65 owing to the engagement of the gears 29 with the rack bar 33. As they pass below the nozzles or jets 32, the articles will be sprayed with the glazing liquid. After leaving this point the articles are carried 70 through the dryer so that by the time they reach the rear end of the machine they will be perfectly dry so that no further treatment of any kind will be necessary. The articles are then lifted from the spindles or 75 supports by a different operator and may be packed in receptacles or placed upon a truck 80 or the like for future disposition.

85 From the foregoing description and a study of the drawings it is apparent that we have thus provided a very simply constructed and consequently inexpensive continuous power driven carrier and apparatus for coating pottery, earthenware goods of all kinds or 90 tiles with the usual liquid employed for giving the desired glazed surface or finish. The device is bound to be a great time and labor saver and owing to the fewness of the parts it is apparent that there is practically little 95 to get out of order.

100 While we have shown and described the preferred embodiment of the invention it is of course to be understood that we reserve the right to make such changes in the form, construction and arrangement of parts as will not depart from the spirit of the invention or the scope of the subjoined claim.

We claim:

105 A device of the character described comprising a supporting frame, an endless conveyor movable therealong and equipped with drive means, a plurality of supports carried by the conveyor and adapted to carry articles to be glazed, shields carried by the frame between which the articles pass, means entering between the shields for spraying glazing liquid onto the articles, a hood through which the articles pass subsequent to spraying, and heating means within said hood whereby to effect drying of the articles. 110

115 In testimony whereof we affix our signatures.

JOHN D. BOWMAN.
THEODOR J. ROTH.
